BERNARD MICHEAL SHEA, OF AMSTERDAM, NEW YORK.

OPEN-MESH KNITTED FABRIC.

1,168,684.

Specification of Letters Patent.

Patented Jan. 18, 1916.

Application filed October 3, 1914. Serial No. 864,921.

To all whom it may concern:

Be it known that I, BERNARD M. SHEA, a citizen of the United States, residing at Amsterdam, in the county of Montgomery and State of New York, have invented a new and useful Open-Mesh Knitted Fabric, of which the following is a specification.

This invention relates to open work or open mesh-fabric, and its object is to provide a finished fabric of the open mesh type having a perfectly smooth and regular appearance.

In accordance with the present invention the loop forming the open mesh is divided equally between the stitches on opposite sides thereof, so that the stitch forming the mesh aperture is not diverted from its natural form of a loop, and it is because of this that the finished fabric has so smooth and regular an appearance.

In the knitting of the porous or open mesh cloth a course is placed on the needles in the ordinary way by means of a plain stitch wheel and the next course is placed on the needles by means of a plugged stitch wheel. Now, by means of spreading or transfer wheels the long stitch of the second course is transferred to needles adjacent to that forming the long stitch, and since in the knitting of the cloth of the present invention two spreading or transfer wheels are employed, one outside and the other inside of the cylinder, the stitch is diverted evenly on opposite sides to engage the stitches being there formed, so that the open mesh is symmetrical and all strains tending to distort the finished cloth are avoided.

The invention will be best understood from a consideration of the following detailed description, taken in connection with the accompanying drawings forming a part of this specification, with the further understanding that while the drawings show a practical form of the invention, the latter is not confined to any strict conformity with the showing of the drawings, but may be changed and modified so long as such changes and modifications mark no material departure from the salient features of the invention.

In the drawings:—Figure 1 is a diagrammatic representation on a greatly exaggerated scale of an open mesh cloth made in accordance with the present invention. Fig. 2 is a face view of one of the transfer wheels. Fig. 3 is an enlarged view of a portion of

the periphery of the transfer wheel shown in Fig. 2.

For convenience of description the stitches are numbered 1, 2, 3, 4 and the courses are numbered 5, 6, 7, 8 and 9. Course 5 is placed on the needles in the ordinary way with a plain stitch wheel, while course 6 is placed on the needles by a plugged stitch wheel, thus forming the long stitch 3^a of course 6 and the long stitches 2^a and 4^a of course 5.

In the knitting machine spreading or transfer wheels 10 are provided, these wheels having relatively wide notches 11 and narrower and deeper notches 12 between the wide notches. These deeper notches 12 define teeth 13 therebetween in the outer ends of which the notches 11 are formed. On one side of each notch 11, that side of the tooth 13 toward the corresponding notch 12 has its outer side beveled as shown at 14, while the other side of the tooth is beveled as shown at 15 oppositely to and more obtusely than the bevel 14. Two spreading or transfer wheels 10 are provided, one operating outside and the other inside of the cylinder. They can be attached either with the first one in order operating outside and the second one inside, as will be assumed in the following description, or vice versa, since they are equally efficient either way. It is the spreading wheels which make the pore or mesh indicated at 16 in Fig. 1 by spreading a long stitch 3^a of course 6 to the adjacent needles forming the stitches 2^a and 4^a of course 5, and these spreading wheels succeed the plugged stitch wheel.

Considering the first transfer wheel as operating outside of the cylinder it engages the needles forming the stitches 2 and 3 and brings the tops of said needles together. The needle holding loop 2^a of course 5 is thereby placed behind the needle forming the loop 3^a of course 6. The loop 3^a now being above the needle forming the loops 2, a small cloth wheel pushes it down hooking loop 3^a over the needle forming the loops 2. A slightly larger cloth wheel now pushes both loops 2^a and 3^a down far enough to hook both under the beard of the needle. Thus the needle forming loop 2 holds its original stitch and also half of stitch or loop 3^a. The second spreading wheel now engages the needles forming stitches or loops 3^a and 4^a and operating in the same manner as the first-named transfer wheel places the needle

carrying loop 4^a behind the needle carrying loop 3^a. A second small cloth wheel pushes loop 3^a down on the needle carrying loop 4^a, thereby looping the stitch 3^a over the needle forming the loops 4^a. The loop 3^a therefore now encircles the needles of loops 2^a, 3^a, and 4^a.

Course 7 is placed on the needles in the ordinary way by a plain stitch wheel, but 10 is pressed off with a cut presser cut 1 and 3 so that loops of the series 1, 2, and 4 are pressed off allowing loop of series 3 of course 7 and also the bottom or closed end of loop 3^a of course 6 to remain on the 15 number 3 needle.

The courses 8 and 9 are placed on the needle in the ordinary way, or they may be eliminated if so desired, since they have no effect on the formation of the mesh.

20 The mesh 16 is symmetrical, while a loop 3^a takes up the loops of course 6 which would otherwise correspond to the series 2 and 4 and engages at the midportion of the bottom about the loop of series 25 3 occurring in course 8. The loops of series 2 and 4 of course 5 are elongated, so that they pass by course 6 without engaging it and are engaged by the corresponding loops of series 2 and 4 of course 7, which 30 also engages the symmetrically expanded loop 3^a of course 6. In course 7 the loop which corresponds to the series 3 and which in the drawings is designated 3^b is also engaged by the corresponding loop of 35 course 8.

Non-symmetrical open meshes require undue stress to be placed upon the needles in the formation of the fabric, and the fabric produced will not be as strong nor as 40 elastic as a fabric having symmetrical open mesh as produced by the present invention. While in certain forms of open mesh fabric as heretofore proposed the whole task of holding a stitch corresponding to the series 3 is imposed upon a stitch of one of the adjacent series when the fabric is knitted and finished, the work of holding and retaining the stitch 3^a of the present invention is divided between 45 50 stitches 2^a and 4^a so that the stitch or loop 3^a is not diverted from its natural form of a loop.

In the cloth or fabric produced in accordance with the present invention the loop 3^a 55 where it crosses the long loops or stitches 2^a and 4^a is not discernible by the naked eye, wherefore the finished fabric has a perfectly smooth and regular appearance.

60 In the foregoing description with reference to the courses and rows of loops or stitches, the upper row only of open meshes is considered. Since the next row of meshes is staggered with relation to the first row the designation of the rows of 65 loops by number does not apply, for in the

second row of meshes laterally expanded loops are in the row 1 instead of the row 3.

The formation of the mesh of the present invention requires the presence of two transfer wheels, and in this respect differs 70 from other mesh formations requiring but one transfer wheel.

What is claimed is:

1. An open-mesh knitted fabric having the yarn of predetermined courses formed at 75 predetermined intervals into symmetrically elongated and spread loops each containing substantially as much yarn as would form three adjacent normal loops of the course, and each elongated and spread loop engaging adjacent loops of the next course and a corresponding loop of the second course in order therefrom and also being free from engagement with any loops of the course of which it is formed.

2. An open-mesh knitted fabric having the yarn of predetermined courses formed at 80 predetermined intervals into symmetrically elongated and spread loops each containing substantially as much yarn as would form three adjacent normal loops of the same course, each of the elongated and spread loops engaging a corresponding loop of the same series in the second course therefrom and also the loop of the same series of the 85 preceding course to the one containing the expanded loop, with those loops of the last-named course on opposite sides of the series containing the expanded loop prolonged beyond the course containing the expanded 90 loop into engagement with the loops of the next course in order beyond that containing the expanded loop.

3. An open-mesh knitted fabric having 95 courses of loops of like size arranged in 100 series, with certain loops of predetermined courses each prolonged beyond the next course in order to the second course therefrom and there engaging the loop of the same series in said second course, and also 105 laterally expanded into engagement with the loops of the series on opposite sides of the series in which the expanded loop is formed, with the loops of the preceding course on 110 opposite sides of the series in which the expanded loop is formed prolonged beyond the course containing the expanded loop into engagement with the expanded loop and with the like loops of the next course in 115 order to that containing the expanded loop.

4. An open-mesh knitted fabric composed 120 of symmetrically spaced courses of symmetrically spaced loops of like size, with certain 125 of the loops of predetermined courses prolonged and symmetrically spaced and expanded into loops of larger area than the others, with each enlarged loop engaging smaller loops of the next course in order on opposite sides of the series of loops of which it constitutes a member and also a smaller 130

loop of the same series in the second course therefrom, said prolonged and expanded loop being free from engagement with any loops of its own course.

5 5. An open-mesh knitted fabric having the openings each formed by a prolonged and laterally expanded loop as wide as three adjacent series of loops and as long as two courses, and engaging loops of the preceding 10 and the two succeeding courses in order and free from engagement with any loops of the same course in which the expanded loop is formed.

6. An open mesh-knitted fabric having 15 the openings each formed by a prolonged and laterally expanded loop comprising a

length of yarn substantially that of three loops of the course from which it springs, said loop being prolonged for three courses in one direction and expanded for a distance 20 represented by three successive series of loops in the other direction and including four successive courses and five loops in its formation.

In testimony, that I claim the foregoing 25 as my own, I have hereto affixed my signature in the presence of two witnesses.
